UNITED STATES PATENT OFFICE.

BERNARD LYNN McNERNEY, OF MINNEAPOLIS, MINNESOTA.

ADJUSTABLE WRENCH.

Application filed September 24, 1923. Serial No. 664,564.

To all whom it may concern:

Be it known that I, BERNARD LYNN McNERNEY, a citizen of the United States, residing in Minneapolis, in the county of Hennepin and State of Minnesota, have invented a new and useful Adjustable Wrench, of which the following is a specification.

My invention relates to improvements in adjustable wrenches.

10 An object is to provide a simple, durable and efficient wrench having a manipulating handle hinged on the body of the device and connected with the jaws thereof through mechanism adapted to open and close said 15 jaws and clamp the same upon an object with force proportionate to that applied to said handle in the working swing of the tool.

Another object is to provide a wrench 20 having yielding means designed to be variously set and adapted to render the tool capable of uniform ratchet-like operation upon objects of different dimensions.

With the foregoing and other objects in 25 view, which will appear in the following description, the invention resides in the novel combination and arrangement of parts and in the details of construction herein-after described and claimed.

30 In the drawings, Fig. 1 is a side elevation of a wrench embodying my invention; Fig. 2 is a plan view thereof; Fig. 3 is a view similar to Fig. 1, the near cover plate being removed to expose parts otherwise concealed thereby; Figs. 4 and 5 are sectional views respectively taken on lines 4—4 and 5—5 of Fig. 2; Fig. 6 is a sectional view taken on line 6—6 of Fig. 2 and Figs. 7 and 8 are detail views of the jaws, showing 40 different relative positions thereof.

Referring to the drawings, it will be observed that my improved wrench includes a body A, end jaws b, c and a handle 10. The body consists of a block 11 and cover plates 12 reaching back from the sides of the block. Said block 11 is formed with parallel ways 13, 13^a transversely thereof and with spaced, parallel guide slots 14, 14^a arranged longitudinally of said body. A bolt 15 reaching through the block 11 and cover plates 12 and a second bolt 16 reaching through said plates tie the block 11 and plates together, lugs 17 on said block being fitted in notches 18 in the plates to supplement said bolts in preventing relative movement between said block and plates.

The jaw b includes a head 19 and shank 20, a similar head 21 and shank 22 comprising the jaw c. The shanks 20, 22 are slideable in the ways 13, 13^a in the block, the shank 20 having cam slots 20^a, 20^b therein, while the shank 22 is formed with cam slots 22^a, 22^b respectively reversed with respect and companion to said slots 20^a, 20^b in the shank 20. Said cam slots are arranged angularly 65 with respect to the direction of movement of the jaws b, c. A pin 23 reaching through companion cam slots 20^a, 22^a in the shanks 20, 22 also extends through the guide slot 14 in the block 11. A similar pin 24 reaches 70 through companion cam slots 20^b, 22^b in said shanks and extends through the guide slot 14^a in said block. Rollers 25, journaled on the block 11 form bearings for the shanks 20, 22 and prevent the binding of the jaws b, 75 c with the block 11.

The handle 10 is hinged at one end between the cover plates 12 by means of a pintle 26, said handle being enlarged at its pivoted end to supply a mounting for a pair 80 of studs 27, 28 which are arranged on opposite sides of said pintle 26. A pair of links 29 join the ends of the pin 23 with the studs 27 on the handle 10 and a second pair of links 30 join the ends of the pin 24 with 85 the studs 28 on said handle. Recesses 31, in the sides of the block 11 provide clearance spaces for the ends of the pins 23, 24 and the forward ends of the links 29, 30. The pins 23 and 24 shifted by the links 29, 30 in 90 the guide slots 14, 14^a and co-acting with the cam surfaces of the slots 20^a, 22^a, 20^b and 22^b open and close the jaws b, c when the handle 10 is swung back and forth on the body A.

A filler strip 32 secured between the cover plates 12 supplies a mounting for a curved spring leaf 33. One end of this spring leaf is fixed to the strip 32 and the opposite end of said leaf slidably bears against said strip. 100 An adjustable stop screw 34, passes freely through the forward, enlarged end of the handle 10. A rectangular aperture 35 in the handle receives an adjusting nut 35^a in which the stop screw 34 is threaded. The 105 spring leaf 33 serves as a yielding abutment for the head 34^a of the stop screw 34 and said screw co-acting with said spring leaf 33, yieldingly opposes the throw of the handle 10 in a direction increasing the opening of 110 the jaws b, c.

In use, the jaws b, c are suitably adjusted

to embrace a nut, pipe or other object by 5
tilting the handle 10 on the body A. An
object to which the jaws b, c are applied is
turned by the application of force upon the
handle 10 in a direction tending to close the
jaws, the resetting of the wrench for a new
power stroke being accomplished by re- 10
versing the force upon the handle and
swinging it in a direction to open the jaws
b, c. During the working swing of the
wrench, the gripping power of the jaws
upon the object increases proportionately
with the force applied to the handle 10, the
return swing of the wrench being initially
15 attended with the opening of the jaws. In
order to limit the opening of the jaws b, c
upon return throw of the wrench, the user
adjusts the stop screw 34 to suit the par- 20
ticular object at hand. In making this ad-
justment the nut 35^a is turned to shift the
screw 34 so that the head thereof will
stand in near proximity to the leaf spring
33 upon the power throw of the handle 10.
Thus located, said screw co-acts with said
25 spring on the return throw of the handle 10
and limits the hinging action of said handle.
Consequently limited, as against separation,
the jaws b, c freely turn back to new grip-
ping position without unnecessary ex- 30
pansion. A yielding ratcheting action may be
simulated by adjusting the screw 34 against
the spring 33, when the jaws b, c are closed
as far as possible upon an object. With
this adjustment, the spring 33 acts con- 35
stantly to "break" the wrench on the axis
of the pintle 26 and thereby close the jaws
b, c. Said spring, however, yields on the
return throw of the handle 10 and permits
the opening of said jaws sufficiently to allow 40
them to slide over the gripping surface of
an object. Being set to "ratchet" upon an
object, the wrench is easily manipulated,
the jaws b, c thereof being automatically ad-
justed during the operation.

45 The automatic gripping of the jaws b, c
upon an object during a working swing of
the handle 10 is an important feature of my
invention. In this connection, attention is
invited to the powerful leverage of the
50 handle 10 upon the links 29, 30 and to the
powerful cam action between said links and
the jaws b, c. Another important feature
resides in the adjustable yielding means,
which adapts the wrench to a uniform
55 ratcheting action on objects of different
dimensions.

Changes in the specific form of my in-
vention, as herein disclosed, may be made
60 within the scope of what is claimed without
departing from the spirit of my invention.

Having described my invention, what I
claim as new and desire to protect by Let-
ters Patent is:

1. In a wrench, a body, a handle pivoted

thereon, jaws carried by the body, one jaw 65
being slidable thereon, jaw shifting means
interposed between the handle and slidable
jaw to vary the jaw opening upon relative
tilting movements of said handle and body,
a spring leaf anchored to the body, a stop 70
screw adjustable in said handle and ar-
ranged to strike said spring, the co-action
of said spring and stop screw serving to
adjustably and yieldingly oppose relative
tilting movements of the handle and body 75
in directions increasing the jaw opening, such
opposition being effected earlier or later
during such movement of said handle and
body according to the adjustment of said
screw. 80

2. In a wrench, a body, a handle pivoted
thereon, jaws carried by the body, one jaw
being slidable thereon, jaw shifting means
interposed between the handle and slidable
jaw to vary the jaw opening upon relative 85
tilting movements of said handle and body,
means associated with said handle and body
for adjustably and yieldingly opposing the
tilting of one member with respect to the
other in a direction to increase the jaw 90
opening, said means comprising a spring
on one member and an adjustable abut-
ment on the other member arranged to co-
act with said spring earlier or later in such
relative tilting movement of said members. 95

3. In a wrench, a body, a handle hinged
thereon for manipulating the tool, a pair
of jaws carried by the body, one jaw being
slidable thereon, means interposed between
said handle and slidable jaw for shifting 100
the latter to vary the jaw opening and to
grip the jaws upon an object during work-
ing throws of the tool and means for ad-
justably opposing the hinging of the handle
on the body and consequently limiting en- 105
largement of the jaw opening during re-
turn swings of the tool, said means provid-
ing for free hinging movement of the handle
with respect to the body through various
initial stages of the return throw of said 110
handle.

4. In a wrench, a body, a handle pivoted
thereon, jaws carried by the body, one jaw
being slidable thereon, jaw shifting means
interposed between the handle and slidable 115
jaw to vary the jaw opening upon relative
tilting movements of said handle and body,
adjustable yielding stop mechanism inter-
posed between said handle and body for
yieldingly opposing the tilting of one mem- 120
ber with respect to the other in a direction
increasing the jaw opening, said mecha-
nism being effective only at predetermined
relative positions of said members.

In testimony whereof I have signed my 125
name to this specification.

BERNARD LYNN McNERNEY.
